UNITED STATES PATENT OFFICE.

MORRIS KATCHER, OF NEW YORK, N. Y., ASSIGNOR TO COLUMBIA METAL BOX CO., OF NEW YORK, N. Y.

QUICK-MAKE-AND-BREAK ELECTRIC SWITCH.

Application filed February 6, 1925. Serial No. 7,327.

This invention relates to improvements in electric switches and has for its object the provision of a hand operated enclosed switch with a quick make-and-break action of simple economical construction, the parts, also, being so arranged as to facilitate assembling. Another object is to provide means whereby the cover of the switch box is locked when the switch is closed. The switch can also be locked in open position when the cover is open.

A switch according to this invention is provided with knife blade switch levers, pivoted to one set of terminals and so connected to an operating handle, that by moving said handle in one or the other direction the switch levers will turn on their pivots and snap into or out of engagement with switch clips carried by an opposite set of terminals.

To prevent burning of the contacts due to extended sparking, a quick motion on the part of the switch levers is ensured in a switch according to this invention by allowing the switch levers to turn on their pivots independently of the operating handle under the action of a compression spring, which is first compressed by moving the handle and then released so as to expand and thereby rapidly turn the switch levers, making or breaking the circuit.

For protection the switch is enclosed in an iron box, the cover of which is locked when the circuit is closed and which can be opened only after breaking the circuit by opening the switch by means of the handle placed outside of the box.

The construction of a switch according to this invention, which will be more fully described hereinafter is illustrated in the accompanying drawings, in which:—

Figure 1 is a plan of the switch, with the protecting top cover removed and the switch levers out of engagement with the switch clips,

Figure 2 is a side elevation of the switch with the switch levers in the same position as in Figure 1 and with the top cover slightly raised,

Figure 3 is a transverse section on line A—A of Figure 1, but with the top cover attached and slightly raised as in Figure 2,

Figure 4 is a side elevation of the switch with the switch levers in engagement with the switch clips and the top cover locked,

Figure 5 is a separate view of the slotted

plate which is fixed to the extension of the switch handle, and

Figure 6 is a separate view of the disk which is rotatably mounted on said extension.

Switch levers 1 are pivoted at one end to terminals 2, which rest on the base 3 of insulating material placed in a sheet metal box 4 and fastened to it by screws 5. Fuses 6 are interposed between terminals 2 and the cable attachments 7. On the same insulating base are arranged terminals 8 connected to the cable attachments 9, and carrying switch clips 10 into which the free ends of the switch levers 1 fit when the switch is closed. Switch levers 1 are tied together by a cross bar 11 of insulating material, which carries a slotted member 12, said member engaging a yoke 13 which is rotatably mounted in box 4, the axis of rotation of said yoke being on a line with the axes of rotation of switch levers 1.

Operating handle 14 is outside box 4 and is supported by means of an extension 15 of said handle, which bears in a hole in the sidewall of the box. Extension 15 has a hole along its axis which forms a bearing for one end of yoke 13, the other end of which rests in a hole in the opposite side wall of box 4. In assembling yoke 13 in the box, one end is inserted in extension 15 and the other end is sprung into the opposite wall of box 4. Loosely mounted on extension 15, near yoke 13, is a disk 16 which is provided with lips 17 and 18 bent at right angles to its main body. Lips 17 and 18 straddle a leg of yoke 13 with extra clearance provided between them to permit appreciable rotation of disk 16 without corresponding rotation of yoke 13 (Figures 2 and 4). Disk 16 is shown by itself in Figure 6 in the same position that it occupies in Figure 2. The hub 40 which is formed integral with disk 16 is rotatably mounted on extension 15.

Plate 19 is fixed to extension 15 just inside of the wall of box 4 (Figures 1 and 3) and serves to prevent extension 15 and with it handle 14 from being separated from box 4. I prefer to fasten plate 19 to extension 15, by forming two flat surfaces on opposite sides of said extension and forcing lips 39 and 37 of plate 19 upon these surfaces (Figures 2 and 4). In addition to holding handle 14 to the switch mechanism, plate 19 is provided with a projection 20 which is adapted to engage a slot 21 in disk 16 for the purpose of rotating the latter from handle 14. Figure 5 shows

plate 19 in the same position that it occupies in Figure 2.

A flat rod 22, one end of which is pivoted to disk 16 has its other end slidably mounted in a guide 23 pivoted to the wall of box 4. A helical compression spring 24 mounted on rod 22 butts with one end against the guide 23, and with the other end against a collar 25 on the rod 22. As spring 24 is always under compression, disk 16 tends to snap to the position either of Figure 2 or Figure 4. Further rotation of disk 16, under the pressure of spring 24 as shown in Figure 2, is prevented by stop 26 fastened to the wall of box 4, which stop 10 engages the flat edge 27 formed in the periphery of disk 16. In a similar manner, further rotation of disk 16 from the position shown in Figure 4, is prevented by flat edge 28 engaging stop 26. Stop 30 is provided to prevent further rotation of handle 14 to the left of the position shown for it in Figure 2.

To prevent opening of the cover 31 when the switch is closed, a pivoted lever 32 is provided having a flange 35 formed at its lower end. The edge of disk 16 is adapted to contact with flange 35 as long as the switch is closed as seen in Figure 4. While in this position notch 34 of lever 32 engages cover 31 at the edge of hole 38 provided in said cover, lever 32 passing through said hole. When the switch is open, notch 36 of disk 16 comes opposite flange 35 permitting the latter to enter releasing thereby notch 34 from cover 31 permitting lever 32 to be rotated so that said 25 cover can be raised. With lever 32 locked with disk 16, the switch cannot be closed while cover 31 is lifted.

The operation of the mechanism is as follows:—

40 Starting with handle 14 in the position shown in Figure 2; rotating said handle to the right carries plate 19 and its projection 20 along with it, until said projection comes up against the forward edge of slot 21 in disk 16. 45 Further rotation of handle 14 carries disk 16 around with it against the pressure of spring 24. Yoke 13 and switch levers 1 are carried along with disk 16. The rotation of disk 16 is against the thrust of spring 24 and rod 22 as 50 long as the line of thrust is above the axis of rotation of yoke 13. When the line of thrust comes below this dead center, the pressure of spring 24 is released causing disk 16 to be snapped around downward to the right, the 55 space in slot 21 from its rear edge to the rear of projection 20 permitting this movement. The snapping around of disk 16 snaps switch levers 1 into switch clips 10 closing the circuits thereby.

60 In opening the switch, handle 14 is rotated to the left of its position shown in Figure 4 carrying with it plate 19 and its projection 20 until the latter comes back against the rear edge of slot 21. Further rotation of handle 65 14 carries disk 16 around with it against the pressure of spring 24 until the dead center, as

explained above, is passed when the pressure of spring 24 is released, snapping around disk 16 and with it switch levers 1 clear of switch clips 10 and breaking the circuits thereby. 70

I claim:

1. A quick make-and-break electric switch comprising circuit terminal contacts, switch levers for opening and closing the circuits between said contacts, a box for enclosing said contacts and switch levers, a handle located outside the box having an extension projecting through one wall of same and rotatably mounted therein, said extension having a necked down portion projecting just within the box, a slotted sheet metal stamping having its slotted portion fitting over said necked down portion within the box, said stamping having a tongue bent up from it and towards the interior of the box, means for operating the switch levers and spring actuated means having a lost motion connection to said operating means for snapping the switch levers into open and closed positions, said spring means being adapted to be tripped by said tongue. 80 85 90

2. A quick make-and-break electric switch comprising circuit terminal contacts, switch levers for opening and closing the circuits between said contacts, a box for enclosing said contacts and switch levers, a handle located outside the box having an extension projecting through one wall of same and rotatably mounted therein, said extension having a necked down portion projecting just within the box, a slotted sheet metal stamping having a forced fit on said necked down portion whereby the handle is prevented from coming away from the box, said stamping having a tongue bent up from it, means for operating the switch levers, and spring actuated means in operative relation to said operating means for snapping the switch levers into open and closed positions, said spring means being adapted to be tripped by 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 vided with a predetermined amount of backlash, and a spring adapted normally to rotate said member in opposite directions about said extension of the handle, said latter rotation being controlled by said engaging means on said extension of the handle.

4. A quick make-and-break electric switch comprising circuit terminal contacts, switch levers for opening and closing the circuits between said contacts, a box for enclosing said contacts and switch levers, a handle located outside the box having an extension passing through one wall of same, rotatably mounted means for operating the switch levers, a member loosely mounted upon said extension, means carried by said extension adapted to engage said member with a predetermined amount of backlash in said engagement, said member adapted also to engage said means for operating the switch levers with a predetermined amount of backlash in said latter engagement, a spring adapted normally to rotate said member in opposite directions about the extension of the handle, said latter rotation being controlled by said engaging means on the extension of the handle, and a stop fastened to the wall of the box, one end of said stop projecting within the box for limiting the rotation of said member in both directions, the other end of the stop projecting outside of the box and adapted thereby to limit the rotation of the handle.
5. A quick make-and-break electric switch comprising circuit terminal contacts, switch levers for opening and closing the circuits between said contacts, a box for enclosing said contacts and switch levers, a handle located outside the box having an extension passing

through one wall of same, a rotatably mounted yoke for operating the switch levers, a sheet metal stamping loosely mounted upon said extension, means, carried by said extension, having a portion engage a slotted hole provided in said stamping intermediate of its bearing upon said extension and its periphery, said hole being sufficiently large to provide lost motion for said portion engaging it, said stamping being provided with a lost motion connection to said yoke, and a spring for rotating said stamping in opposite directions past a dead center, said latter rotation being controlled by said engaging portion.

6. A quick make-and-break electric switch comprising circuit terminal contacts, switch levers for opening and closing the circuits between said contacts, a box for enclosing said contacts and switch levers, a handle located outside the box having an extension passing through one wall of same, a rotatably mounted yoke for operating the switch levers, a sheet metal stamping loosely mounted upon said extension, another sheet metal stamping fixedly mounted upon said extension between said loose stamping and said wall of the box, said fixed stamping being provided with a tongue projecting inwardly of the box and engaging a slotted hole provided in said loose stamping, said hole being sufficiently large to provide lost motion between said stampings, said loose stamping being provided with a lost motion connection to said yoke, and a spring for rotating said loose stamping in opposite directions past a dead center, said latter rotation being controlled by the tongue of said fixed stamping.

MORRIS KATCHER.
